MANIFOLDING ATTACHMENT FOR TYPE-WRITERS

Marcus S. Roosevelt, Highland Park, Mich., assignor to The Hamilton Autographic Register Company, Hamilton, Ohio, a corporation of Ohio

Application November 15, 1934, Serial No. 753,186

3 Claims. (Cl. 197—134)

This invention relates to a fixture for convenient attachment, particularly to a commercial typewriter having a cylindrical rotatable impression platen, for rotatively carrying a plurality or 5 series of reeled transfer or carbon strips to be interleaved with continuous webs or strips of stationery for making manifold or duplicate copies.

It is quite expedient to use continuous or strip form of stationery in commercial typewriters having a cylindrical rotatable impression platen, these strips usually containing printed forms arranged in a consecutive order longitudinally of the strip, and the forms adapted to be consecutively torn off from the strip after the writing space thereof has been filled in or typed.

For making duplicate copies, carbon sheets are interleaved between a selected number of continuous form of stationery or work strips. In the use of loose carbon sheets difficulties are encountered in removing the sheets from a section or form length of the work strips that have been typed, and to transfer the same to a new position for writing upon a succeeding portion of the work strip. To obviate some of these difficulties, fixtures are employed providing a moving carrier to which one end of the carbon sheets are attached for withdrawing or pulling back the carbon sheets to position the same for a succeeding form or section of the work strip. Fixtures of this class are cumbersome, require considerable length to accommodate for the required travel of the carrier governed by the length of carbon sheet, and are burdensome to the carriage of the typewriter, and if wholly sustained thereon are 35 very unstable.

Accordingly, a principal object of this invention is to overcome undesirable features of apparatus of the class referred to, and to provide a simple, light-in-weight, compact fixture readily and conveniently applicable in the preferred embodiment upon the carriage of a commercial cylindrical platen typewriter in which the manifolding or transfer medium is in the form of a strip, reel wound, unreeled with the feeding advance of the 45 work strips, with which the unreeled portion thereof is interleaved and re-reeled for withdrawing or retracting the carbon strip to reposition an unreeled portion thereof into a proper position with a succeeding portion or section of the 50 work strips.

Another object of the invention is to provide a fixture for mounting upon the carriage of a commercial typewriter with one or a plurality of reels each carrying a strip of carbon paper adapted as unreeled to be interleaved with continuous

stationery or work strips and travel therewith by the feeding influence of the typewriter platen, the reels under control and in transmission with a common actuator for simultaneously re-reeling the carbon strips and repositioning the same with succeeding portions or sections of the work strips to continue the typing thereon.

Another object of the invention is to provide a carbon strip for manifold typing or writing continuous stationery or work strips, the carbon strip 10 reel wound upon a spool for packaging and merchandising and with the spool insertable into a fixture for unreeling to interleave with continuous work strips and subsequently re-reeling the carbon strip to reposition the same between a 15 succeeding portion or section of the work strips and allow a tear-off for the portion or section of the work strip upon which the writing has been completed.

Other features and advantages of the invention 20 are more fully set forth in a description of the accompanying drawings, in which:

Figure 1 is an end elevation of the improved transfer sheet or web reel as applied on the carriage of a commercial typewriter, a typewriter 25 likewise being illustrated in end elevation more or less diagrammatically.

Figure 2 is an enlarged end view of the reel, showing the operating lever locked at one end of its stroke.

Figure 3 is a front elevation of the reel.

Figure 4 is a detail side elevation of a portion of an end frame of the reel at a side opposite to that shown in Figure 2.

Figure 5 is a section on line 5—5, Figure 3.

35

Figure 6 is a section on line 6—6, Figure 3.

Figure 7 is a section on line 7—7, Figure 2.

Figure 8 is a section on line 8—8, Figure 7.

Figure 9 is a sectional view partially corresponding to Figure 7, illustrating a step in the 40 method of removing a spindle and its spool from the reel frame.

Figure 10 is an enlarged section on line 10—10, Figure 6.

30

Figure 11 is a section on line 11—11. Figure 10. 45

Figure 12 is a central longitudinal section through the spool carried by a spindle and taken on line 12—12, Figure 5.

Figure 13 is a section on line 13—13, Figure 12.

Figure 14 is a diagrammatic section taken on 50 line 14—14, Figure 1, illustrating the method of inserting or removing a spindle with its spool.

Figure 15 is a longitudinal section through the reel operating handle de-clutched from the spindle transmitting gear.

55

Figures 16 to 20 inclusive are diagrammatic views illustrating various stages of operation of the devices, Figure 16 thereof showing the operating lever locked against motion, while the work strips are being manually advanced for engagement about the typewriter platen as the initial step in loading.

Figure 17 illustrates the operating lever unlocked, allowing the carbon strips of the several reels to be advanced and positioned between work strips.

Figure 18 shows the work and carbon strips engaged about the typewriter platen and advanced, thereby unreeling the carbon sheets and advancing the work strips from the supply source.

Figure 19 illustrates the handle as moved by the operator in a downward direction to retract the carbon or manifold strips for repositioning the same.

Figure 20 shows the work strips held against retraction by the tension devices of the typewriter against the printing platen, while the carbon strips are being retracted.

Referring to the drawings, 1 indicates a commercial typewriter with a crosswise travelling carriage 2 carrying a rotative cylindrical impression platen 3 about which the stationary or continuous work sheets 4 are engaged in the usual manner for typing thereon. Carbon or transfer sheets or webs are interleaved between the several work strips in the customary manner for making manifold copies of the typing impression.

The carbon or transfer sheets or strips for the number employed are carried by a reel mounted upon the carriage of the typewriter, each transfer sheet wound upon its own core or spool journalled within the framing of the reel. The cores or spools spaced for passing or threading the work strips therebetween for interleaving the carbon or transfer sheets and therewith extend to and about the impression platen of the typewriter, advancing with the work strips as the data is being typed thereon.

The reel comprises a pair of side frames 5, 6 of curved design in plan, each from a lower end having an angular bracket arm 7 extended therefrom downwardly and at an angle forwardly, for attachment respectively to the carriage framing or to appropriate established points on the carriage with which connections can be readily and securely made.

In the present instance the forward ends of both bracket arms are notched or slotted to socket over a rigid cross rod 8 of the typewriter carriage framing and rest upon a flange cross rail 9 of the carriage framing, as illustrated in Figure 5, and clamped thereto by a clamp plate 10 secured to the arm by a screw 11. In this manner the reel can be quickly installed upon and removed from the typewriter carriage and without obstruction or interference to the operation of the working parts of the typewriter carriage nor disturb the key shift of the impression platen. The side frames 5, 6 are connected by several cross rods 12, 12 for determinately spacing the same and forming a rigid frame structure.

Each side frame is provided with a rearward extension 13 carrying a perpendicular depending guide bar 14 longitudinally slotted for slidably sustaining one end of a tension roller 15 extending between the guide bar 14 of the reel framing, and about which the continuous work strips are engaged and looped, as shown in Figure 5, for applying tension thereto. The work strips are advanced from a supply stack or pack when flat

packaged, as shown in Figure 1, or from a roll as another way in which this type of material is packaged for merchandising. The work strips from the supply source are preferably positioned or stationed at a point below the reel to allow draping over a roller 16 journalled in the side frame of the reel framing at the extreme end of the extensions 13 of the side frames, thence extend downwardly over and about the tension roller 15, and thence upwardly to the reel.

The lowermost or first strip 17 of the series which may be designated the "original" and outermost when threaded about the typewriter platen 3 extends from the tension roller 15 upwardly over a frame cross rod 12; thence forwardly over the guide roller 18 journalled in the lower forward end of the reel framing and continues downwardly to and about the typewriter platen 3.

The strip 17 thus directly receives the typing impressions which is transferred to the second or other strips through the medium of the transfer or carbon strips interleaved between the work strips. The strips are pressed against the typewriter impression platen by tension or front and rear feed rolls 19, 20, commonly employed in typewriting machines, and which can be released to free the paper by depressing a finger key.

The frame of the reel supports and journals a plurality of spindles 21, upon each of which a strip of transfer paper is reeled. The spindles are suitably spaced apart and arranged in an arc adapting the same to be transmittingly connected or geared to a master gear for simultaneous rotation of all of the spindles.

As shown, the reel is provided with five spindles. The number, however, is optional depending upon the number of second strips for making the manifold copies desired from one typing. This is somewhat limited by the capacity of the typewriter and the character of the work, for if the typing is to be in definite spacing in which accuracy of registration between the corresponding spacing of the several work strips is necessary, the number must either be reduced or frequent relative adjustment must be made to account for a differential in the advance of one work strip over another, primarily due to a change in the feeding diameter caused by dispensing the sheets one upon another about a rotating cylinder.

Each spindle carries a spool or core upon which a strip length of carbon or manifold paper 22 is reeled and therefrom extended for interleaving between a pair of work strips, and therewith advanced with the feeding rotation of the typewriter platen. As the spindles and parts thereof are duplicate of one another, detailed description thereof will be confined only to one of them.

A spindle 21 at its opposite ends is removably journalled in the side frames of the reel and as shown in Figures 7, 9, and 14, at one end is engaged through a support aperture in the side frame 5 while its opposite end is engaged through an angular aperture 23 in the side frame 6, covered by a swinging closure plate 23a on the aperture side of the side frame 6. To remove the spindle from the reel frame it is moved axially until withdrawn from the journal aperture in the side frame 5 whence it can be swung to an angle to clear the side frame 5, and thence withdrawn longitudinally from the side frame 6.

The spindle 21 intermediate of its length is provided with a spherical enlargement 24 serving

as a fulcrum for a cylindrical core or spool 25 engaged over the spindle as shown in Figure 12. The spherical enlargement 24 is provided with a spring urged detent 26 projected radially therefrom for engagement into an aperture in the core for locking the core against longitudinal displacement and allowing the core to teeter upon the spherical enlargement.

A transfer or carbon strip 22 is wound upon the periphery of the spool 25, the spool preferably as a paperboard product of low cost is employed in packaging the carbon strip for merchandising and provides convenience to the user. In renewing, it eliminates winding the carbon strip upon a permanent spool by the user which would be troublesome and possibly destroy the efficiency of the apparatus, for if carelessly applied it may be difficult to maintain alignment with the work sheets.

20 In spooling the carbon strip, a considerable length can be employed accommodating for typing a number of form lengths of the work strip, before making a tear-off of the type forms and re-reeling the carbon strip for reuse between subsequent form lengths of the work strip, or if a tear-off is made for each form length of the work strip as typed consuming only a section of the carbon strip, it allows for a considerable reserve supply so that quite a number of 25 worn sections can be torn from the carbon strip before the supply is diminished to require replenishing. This offers a greater carbon capacity over the prevailing types of devices using the carbon paper in sheet size or lengths.

30 After the carbon strip has been unreeled from the spool the detent 26 will be exposed and can be easily depressed, as with the aid of a point end of a pencil, to release the spool for spool withdrawal. For inserting a spool, the detent is 35 manually depressed to allow it to enter the bore of the spool and the spool slid over the spindle until the detent comes into registry with the orifice, whence it will snap into the orifice locking the spool upon the spindle. The teetering of 40 the spool upon the spindle provides for a slight lateral adjustment of the strip without throwing a strain more toward one end of the reel than toward the opposite end, as well as accommodating for variations in tautness of reeling 45 or pull when un-reeling which may tend to disturb the aligning traverse of the strip either when reeling or un-reeling. It thus serves as an equalizer, assuring more beneficial and efficient results than can be obtained by having the 50 spindle rigidly or non-swayingly journaled.

55 The spool through the spindle is positively rotated for reeling or retracting the strip to withdraw the same from a type form or section of the work strips for reuse with a subsequent 60 form or section of the work strip by a pinion 27 mounted upon one end of the spindle and in mesh with a gear 28 journaled in the side frame 5. The gear 28 is common to all the spindles of the series for simultaneous transmission or control.

65 The pinion 27 is preferably loosely mounted upon the spindle and engaged or fixed to one end of a spring 29 encircling the spindle at one side of the pinion, and the opposite end of the spring 70 is fixed to the spindle yieldingly connecting the pinion and spindle for a partial rotation of the pinion. The pinion is provided with a pair of spaced pins 30—30 laterally extending from one side thereof for alternately engaging with a pin 75 or lug 31 radially extending from the spindle

between said pins, limiting or governing a starting or compensating partial rotation of the pinion before the two parts are positively connected.

The master gear 28 is fixed to a stud shaft 32 journaled with and extending through the side frame 5. The outer end of the stud shaft is squared and carries a toothed or notched clutch disc 33 engaged with the square end of the stud shaft, and straddled by a forked end of a hand lever 34 journaled or swiveled upon the stud 10 shaft 32.

15 The lever 34 is provided with a spring-urged clutch bar or lock plunger 35 slidably mounted within the hand lever, as shown in Figures 7 and 15. The lock plunger 35 is adapted to be engaged with a notch in the clutch disc for connecting the lever with the gear 28. The plunger has a knob 36 fixed thereon and extending laterally therefrom through an elongated slot in the hand lever for manually retracting the plunger 20 to disconnect the lever from the clutch disc and gear 28. The plunger is also provided with a laterally extended pin 37 projected through an elongated slot in the hand lever 34 for cooperation with a latch plate 38 fixed to the outer side of 25 the side frame 5 for locking the plunger in clutch connection with the clutch disc at one end of a manipulating stroke of the lever, locking the master gear and pinions of the several spindles in connection therewith against rotation.

30 Referring to Figures 16 to 20 inclusive, diagrammatically portraying the carbon strip reel in various stages of operation and from which the mode of operation will be more readily understood, Figure 16 thereof shows the hand lever 34 35 in a downward position at the end of a manipulating stroke and locked to lock the spools and transmission mechanism therefor against rotation for loading the work strips through the reel and to adjust the same with the carbon strips for 40 bringing the forms into registry, and the carbon strips appropriately from the forward ends of the work strips. A necessary length or section of each of the carbon strips preliminarily having been 45 unreeled with their free ends brought into regis- try or alignment.

45 The work strips in their order are appropriately threaded through the reel, the original or first strip extending from the tension roller 15 over the guide rod 12 and guide roller 18, and a second work strip from the tension roller 15 over the reel portion of the first carbon strip thence over the guide roller 18, and correspondingly in an order for the remaining work strips of the 50 number employed, each second work strip being 55 engaged over an appropriate reeled portion of a carbon strip to interpose or interleaf the carbon strip between two adjoining work strips.

55 After the loading adjustment has been made, the hand lever 34 is disengaged from the notch 60 of the latch plate, whereupon the work strips and the carbon strips are free to be threaded about the typewriter platen to an appropriate degree for starting to type. The work strips and carbon strips with the rotating feed of the typewriter platen are free to traverse the carbon strips, unreeling, rotating the master gear and the operating handle 34 in a clockwise direction for the length of the form or section of work strips to be 65 typed. The hand lever, at the discretion of the operator, can be released from its locking connection with the clutch disc for any prescribed length of work strip to be typed, thus the strips 70 can be advanced or fed to accommodate for typ- 75

ing upon several consecutive forms before making any readjustment of the carbon strips.

Assuming that the work strips are advanced completing the typing upon a prescribed form length and which it is desired when the typing is completed to tear off from the continuous strip, the hand lever 34 is engaged with the clutch disc and moved in a counter-clockwise direction as illustrated in Figure 19, and by releasing the tension rollers of the typewriter and withholding reTRACTING motion of the work strips, as by manually grasping their protruding ends, the carbon strips can be retracted between the typed portions of the work strips and at the same time reeled for positioning between a subsequent or succeeding form length of the work strips.

Having described my invention, I claim:

1. A fixture for mounting upon the carriage of a typewriter, comprising, a frame, a spindle journaled in the frame, a tubular spool removably engaged over said spindle and rotatively connected thereto, the connection providing for teetering the spool upon the spindle, and a strip of manifolding material reeled upon said spool for unwinding therefrom and interleaving be-

tween a pair of strips of stationery to advance therewith about the platen of a typewriter, and adapting the unreeled portion of the manifolding strip to be subsequently re-reeled for retracting and repositioning the same between a succeeding portion of the strips of stationery.

2. A fixture for mounting upon the carriage of a typewriter, comprising, a frame, a spindle removably journaled on said frame, a spool removably engaged upon said spindle and teetering thereon, a strip of manifolding material reeled upon said spool for unwinding therefrom and interleaving between stationery to advance therewith about the platen of a typewriter and adapting the unreeled portion of the manifolding strip to be subsequently re-reeled for retraction from the stationery, and means for rotating said spool.

3. A fixture for mounting upon a carriage of a typewriter, comprising, a frame, a spindle journaled in said frame, having a peripheral enlargement, and a spool for reeling thereon a strip of manifolding material, the spool engageable over the spindle, teetering upon said enlargement and rotatively connected therewith.

MARCUS S. ROOSEVELT.
